UNITED STATES PATENT OFFICE.

WILLIAM S. McLEWEE, OF NEW YORK, ASSIGNOR TO JACOB J. NICHOLS,
OF BROOKLYN, N. Y.

DESIGN FOR A MANTEL ORNAMENT.

SPECIFICATION forming part of Design No. 12,340, dated July 5, 1881.

Application filed April 28, 1881. Term of patent 7 years.

To all whom it may concern:

Be it known that I, WILLIAM S. McLEWEE, of New York, in the county and State of New York, have originated a new Design for a Man-
tel Ornament, of which the following is a speci-
fication.

The mantel ornament to which my design
relates consists of a base-piece, a clock erected
on such base-piece, and two match or lighter
receptacles arranged adjacent to the clock on
the base-piece.

The accompanying drawing represents a
front view of a mantel ornament embodying
my design.

15 A designates a base-piece, which may be
made of metal, and which, as shown, bevels
or tapers upward and is supported on ball-
shaped feet *a*.

20 B designates a clock, having a body of cylin-
dric form, erected on a support or column, C
C' C², extending from the base-piece A. The
bottom section, C, preferably consists of pol-
ished sheet-brass, and is of circular form. It
25 comprises two contiguous beads, *b*, an upper
beveled portion, *c*, corresponding to the bevel-
ed base-piece A, two beads, *d*, above the
same, and a surmounting band, *e*. The body-
section C' is made of silicious material, and
is decorated in a color or colors contrasting
30 with its color. The top section, C², is prefera-
bly made of polished brass, and consists of a
band, *f*, an upper beveled portion, *g*, corre-
sponding to the bevel of the base-piece A, a
fillet, *h*, and a ball, *i*, which is in keeping with
35 the feet *a* of the base-piece.

D designates two standards, arranged one
on each side of the clock-support and connect-
ed to the sides of the clock-body. Each is
made in the form of two vines converging up-
40 ward and meeting just below the clock-body.
At their junction with the clock-body are
balls *j*.

E E' E² designate two match or lighter re-
ceptacles, arranged on the base-piece A, one

on each side of the clock. Each consists of a 45
bottom section, E, which may be of polished
brass, and comprises a bead, *k*, a body-section,
E', which may be made of silicious material
decorated in a color or colors contrasting with
its color, and a top section, E², which may be 50
made of polished brass. The top section, E²,
has a bead, *l*, two pendent portions, *m*, corre-
sponding in outline to the convergence of the
vines, forming the standard D, and two balls, *n*.

It will be seen that I thus produce a very 55
beautiful mantel ornament.

In using the term "silicious material," I
mean to include all such material, even though
it be in the form of an enamel.

What I claim as my design, and desire to 60
secure by Letters Patent, is—

1. A support for a clock, composed of metal
and silicious material decorated in a color or
colors contrasting with its color, substantially
as specified.

2. A supporting-column for a clock, com-
posed of metal and silicious material decorated
in a color or colors contrasting with its color,
and two side standards extending to the clock,
substantially as specified.

3. The clock-supporting column, consisting of
the metal bottom and top sections, C C², and the
body-section, C', composed of silicious mate-
rial decorated in a color or colors contrasting
with its color, and the side standards, D, sub-
stantially as specified.

4. The clock-supporting column, composed
of metal and silicious material decorated in a
color or colors contrasting with its color, and
the receptacles for matches or lighters, ar-
ranged one upon each side of said column, and
also composed of metal and silicious material
decorated in color or colors contrasting with
their color, substantially as specified.

W. S. McLEWEE.
